HANDLE MECHANISM

Ben F. Johnson, Cambridge City, Ind., assignor
to National Metal Products Co., Inc., Conners-
ville, Ind., a corporation of Indiana

Application January 2, 1937, Serial No. 118,853

5 Claims. (Cl. 16—112)

This invention relates to handle mechanisms, and in particular to handle mechanisms of the swinging bar type intended principally for use with caskets.

Handles of the swinging bar type have become popular in connection with caskets, both because of the neat appearance afforded and because of the smaller vault space required. The appearance feature is of course important because of the personal sentiment attached to the selection of a casket. The smaller vault space feature is important particularly in large urban communities.

With the old stationary type handle, in order to provide sufficient hand space for ease in lifting, the over all dimensions of the casket had to be increased. This required a correspondingly larger vault, which in the larger urban communities became a prohibiting factor in many cases. With the advent of the swinging bar type, which swings out while lifting the casket and drops back when idle, smaller vaults are required than with the old stationary type handles. The resulting saving to the individual in individual cost, as well as to the public in the resulting increase in burial space, is at once apparent.

Having in mind the dual requirement of appearance and compactness, it is a principal object of the present invention to provide an improved handle mechanism of the swinging bar type which can be manufactured at low cost, which is rugged, which is unusually compact, and which can be made in a variety of attractive designs.

A further object of the invention is to provide a handle mechanism of the above type comprising a plate or base member which can be readily and quickly assembled with a swinging arm member without requiring such assembly items as screws, bolts, clamps, auxiliary hinges, or the like.

A still further object is to provide such a handle mechanism comprising a plate or base member, a swinging arm member, and a lifting bar, wherein the arm member is assembled with the plate member by passing through an aperture or opening in the plate member from the back side thereof, and is positively held in assembled relation therewith by attaching the lifting bar to the arm member while swung through the opening to the front side of the plate member.

These and other objects are attained in the embodiments of the invention illustrated in the attached drawings, wherein,

55 Fig. 1 illustrates a handle mechanism embody-

ing the present invention and attached to a casket.

Fig. 2 is a perspective view of a plate or base member in the process of being assembled with an arm member.

Fig. 3 is a side elevation of an assembly of a plate member and an arm member, with the arm member in its lower or idle position.

Fig. 4 is a similar side elevation showing the arm member in its raised or lifting position.

Fig. 5 is a rear elevation of the arm member per se.

Fig. 6 is a rear elevation of the plate member per se.

Figs. 7 and 8 are two views of an arm member formed from sheet steel.

Fig. 9 illustrates a plate member also formed from sheet steel.

Referring now to Fig. 1, a casket is indicated, rather diagrammatically, at 10 as having attached to one side thereof plate or base members 11, with which cooperate arm members 12. Carried by the two arm members is a lifting bar 13. While only two sets of plate and arm members are shown attached to the casket, as many may be employed as found desirable.

The plate and arm members may be made of cast metal, preferably die cast, or of sheet steel or the like. In Figs. 2 to 6 I have illustrated these members as being die cast, and preferably cast according to the process commonly known as "slush molding", that is, wherein the interior hot metal is dumped as soon as the metal adjacent the outer surface has chilled sufficiently to form a hollow casting with walls of the desired thickness.

The plate or base member shown in Figs. 2 to 4 and 6 may be cast with a flat, or other shaped, rear side suitable for mounting against an outer wall of the casket. The body of the member may take any desired shape, but the central portion must be provided with an opening or aperture as indicated at 15. In the embodiment shown, I prefer that this opening be rectangular in shape and have side walls 16. In each side wall are cast two recesses or slots 17 and 18. The slots 17 are directly opposing, as are the slots 18 also.

The slots 17 are hinge-forming slots, as will more fully appear presently, while the slots 18 are stop-forming slots. It will be observed that both slots are open-ended to the rear of the plate member, and that the slots 17 have a rounded end wall 19, whereas the slots 18 have an inclined end wall 20. The purpose of this will appear later.

The front side of the plate or base member 11 is dished at 21, on either side of the opening 15, as best shown in Figs. 3 and 4. At the bottom of each dished portion is a countersunk screw hole 22 through which screws are inserted for securing the plate member to a casket, or other body to be lifted.

When the plate member is cast by the "slush molding" process, the interior metal is dumped 10 leaving openings 25, thus producing a hollow casting, light in weight, but still rugged and possessing the necessary strength.

Considering now the arm member shown in Figs. 2 to 5, this member is preferably also cast 15 by the "slush molding" process, leaving opening 26 (see Fig. 5). The arm member preferably has flat side walls 27, spaced apart a distance slightly less than the width of the opening 15 in the plate member 11 so that the arm member may readily 20 pass through the opening.

Projecting from each of the side walls 27 are lugs 28 and 29. The two lugs 28 are directly opposite one another, and have a diameter such that they readily interfit with the hinge-forming slots 25 17 in the plate member. The lugs 29 are also oppositely spaced, and may be of several configurations so long as they will pass into the stop-forming slots 18 in the plate member.

What will be termed the lower or lifting bar 30 end of the arm member 12 is provided with a transversely extending, oval shaped, aperture 30, which is adapted to receive the lifting bar 13. The other or upper end of the arm member is recessed at 31.

When the plate and arm members 11 and 12 are to be assembled together, the plate member is held so that the holder faces the rear side 14, as shown in Fig. 2. The arm member is then grasped so that the upper end may be passed through the 40 opening 15 in the plate member, the arm member being guided so that the lugs 28 engage the hinge-forming slots 17. The arm member is then swung into the opening to the lower or idle position, swinging on the lugs 28, and the recess 31 receiving the rim bordering the opening at the top, as is shown in Fig. 3. The plate member may now be secured to the casket or other body.

When attaching the lifting bar 13 to the arm member, the arm member is preferably swung to the front side of the plate member as shown in Fig. 4, and the lifting bar then inserted through the aperture 30 and held in place by set screws (not shown) or other means. The plate and arm members will then be locked together in assembly, 55 and cannot be disassembled until the lifting bar has been removed.

When a handle mechanism embodying the plate and arm members described has been secured to a casket, as shown in Fig. 1, the lifting bar 13 is 60 permitted to drop to its lower or idle position so long as the casket is at rest. Due to the presence of the dished portion 21 in each plate member 11, which dished portion preferably conforms to the contour of the lifting bar 13, the lifting bar is 65 nearly in flush relation with the front surface of the plate member. This obviously conserves space.

When the casket is to be lifted, the lifting bar is grasped and the arm member swung outwardly 70 until the stop lugs 29 engage the end walls 20 of the stop-forming slots 18, as shown in Fig. 4. The lifting bar is then in the lifting position and it will be observed from Fig. 4 that ample hand room is provided. When the lifting bar is released it will drop to its idle or flush position due

to gravity effect. The over all dimensions of the casket will then be a minimum.

Instead of making the plate and arm members of cast metal, I may form them from sheet steel or other sheet metal, as indicated in Figs. 7, 8, 5 and 9. Figs. 7 and 8 show, respectively, rear and side elevations of the arm member while Fig. 9 shows a rear elevation of the plate member. With the exception of a portion of the arm member the parts of the pressed metal members are the same 10 as for the cast members, and like parts have been designated by like numerals with a prime added.

The pressed metal arm member differs from the cast arm member in that the lifting bar aperture 30 is formed by bending a strap portion 33 as 15 shown in Figs. 7 and 8, and locking it in the bent position by suitably bending lugs 34 extending from the side walls 27' down over the strap portion. Other lugs 35 may extend out from the strap portion and interlock with the lugs 34.

The pressed metal members will of course be hollow, but as will be readily understood will be durable and will possess high strength. Some difficulty may be experienced in forming lugs on the pressed metal arm member corresponding to 25 lugs 28 on the same cast member. For this reason I believe that it is better to establish these lugs by pressing a steel pin 28' in holes in the side walls 27' of the arm member, as shown in Figs. 7 and 8. All other parts can be readily formed 30 from the parent metal during the forming operations.

While I have described and illustrated my invention with particular reference to a specific type of handle mechanism, it will be apparent that 35 many modifications thereof may be made and I do not desire to be limited to the specific embodiment shown, or otherwise than according to the spirit and scope of the appended claims.

What I claim as new and desire to secure by 40 Letters Patent is:

1. In a handle mechanism, in combination, a plate member having an opening therein and being adapted to be secured to an object to be lifted, and also being provided with two sets of 45 slots therein, an arm member for cooperating with said plate member and being provided with two sets of lugs, said lugs and slots being so constructed and arranged as to provide for assembly of said arm member with said plate member by 50 passage of the arm member through said opening from the back side of the plate member, one set of said lugs engaging one set of said slots to form a hinge connection for the assembly, and the other set of said lugs engaging the other set of 55 slots as said arm member swings through said opening to the front side of said plate member, to provide a stop for movement of said arm member.

2. In a handle mechanism for a casket, in combination, a base member adapted to be secured 60 on its rear side to a casket, said base member having an opening extending therethrough and having two sets of transversely extending slots, each of the slots being open-ended to the rear side of said base member, an arm member having 65 projecting transversely therefrom two sets of lugs, one set of said lugs being engageable with one set of said slots as said arm member is passed through said opening from the rear of said base member to form a hinge connection therebetween, and the other of said sets of lugs engaging 70 said other set of slots when said arm member has been swung through a chosen angle to the front side of said base member, and a lifting bar carried by said arm member, said base and arm 75

members being so constructed and arranged as to permit said bar to be in substantial flush relation to said base member when said arm member rests in said opening.

- 5 3. In a handle mechanism for a casket, in combination, a base member adapted to be secured on its rear side to a casket, said base member having a rectangular opening extending therethrough, the long sides of said opening being provided with 10 a set of hinge-forming slots therein and a set of stop-forming slots therein, both set of slots being open-ended to the rear side of said base member, a swinging arm member having a first set of lugs adapted to engage said hinge-forming slots as 15 said arm member is passed through said opening from the rear side of said base member, and also having a second set of lugs adapted to engage said stop-forming slots when said arm member is swung to a lifting position to the front side of 20 said base member, and a lifting bar for attachment to said arm member when swung to the front side of said base member and being operable to hold said base member and arm member in assembled relation.
- 25 4. A handle mechanism comprising, in combination, a plate member adapted to be secured to an object to be lifted, an arm member cooperating with said plate member, said plate member hav-

ing a set of open-end, hinge-forming recesses and a set of open-end, stop-receiving recesses therein, and a set of hinge elements and a set of stop elements on said arm member being slidable into and interfitting with said hinge-forming recesses 5 and said stop-receiving recesses, respectively, when said plate and arm members are assembled together.

5. A handle mechanism comprising, in combination, a plate member adapted to be secured to 10 an object to be lifted, an arm member cooperating with said plate member, said plate member having a set of open-end, hinge-forming recesses and a set of open-end, stop-receiving recesses therein, and a set of hinge elements and a set of 15 stop elements on said arm member being slidable into and interfitting with said hinge-forming recesses and said stop-receiving recesses, respectively, when said plate and arm members are assembled together, said stop-receiving recesses 20 having end walls so arranged that as said hinge elements slide into and interfit with said hinge-forming recesses said arm member may be swung through a predetermined angle and then be arrested by engagement of said stop elements with 25 said end walls.

BEN F. JOHNSON.
